UNITED STATES PATENT OFFICE.

LA VERNE SIMPSON AND JACOB STEIN, OF PITTSBURG, PENNSYLVANIA.

METALLIC TIE AND RAIL-FASTENER.

No. 853,741.

Specification of Letters Patent.

Patented May 14, 1907.

Application filed February 11, 1907. Serial No. 356,752.

To all whom it may concern:

Be it known that we, LA VERNE SIMPSON and JACOB STEIN, citizens of the United States of America, residing at Pittsburg, in the county of Allegheny and State of Pennsylvania, have invented certain new and useful Improvements in Metallic Ties and Rail-Fasteners, of which the following is a specification, reference being had therein to the accompanying drawings.

This invention relates to metallic ties and rail fasteners, and the invention has for its object to provide a simple and inexpensive metallic tie made from a single piece of metal and provided with integral rail fasteners.

Our invention aims to employ a series of ties for supporting and locking rails thereon, the rail fasteners of said ties being arranged whereby they will firmly hold a rail and prevent its lateral and vertical displacement.

To this end, we have devised a light and durable tie especially constructed to engage in the ballast of a roadbed and prevent the tie from creeping or moving when once positioned.

Our improved ties are also constructed whereby the gage of the track can be easily and quickly determined.

The detail construction entering into our invention will be hereinafter more fully described and then specifically pointed out in the appended claims, and referring to the drawing forming part of this specification, like numerals of reference designate corresponding parts throughout the several views, in which:—

Figure 1 is a perspective view of a series of ties constructed in accordance with our invention, illustrating a section of a track supported by said ties, Fig. 2 is a cross sectional view of a track constructed in accordance with our invention.

To put our invention into practice, we construct our improved ties of light and durable metal, which is cut, pressed and punched to provide a tie having a body portion 1, depending sides 2, and angularly disposed ends 3, said ends being of a greater depth than the sides 2 in order to engage in the ballast of a roadbed and prevent longitudinal displacement of the tie. The sides 2 of the tie also assist in preventing lateral displacement.

In forming the tie, the body portion 1 is punched as at 4, to provide upwardly extending lugs or protuberances 5 and 6, the protuberance 6 (see Fig. 2) serving to hold

the outer side of the rail 7, while the protuberance 5 holds the inner side of the rail 8. The rails 7 and 8 constitute a track, and the protuberances 5 and 6 gage the width of said track.

The tie during its formation is also cut or sheared as at 9, and the sheared or cut material bent to form fasteners 10 and 11, the fastener 10 holding the inner side of the rail 7, while the fastener 11 holds the outer side of the rail 8.

It is essential that in order to hold the rails 7 and 8 firmly upon a tie, that a series of ties be used, and alternately arranged with respect to the fastening means. In the laying of the ties, each alternate tie is reversed, whereby the rails will be held alternately by the fasteners 10 and 11, and the protuberances 5 and 6. This arrangement of the ties is clearly illustrated in Fig. 1 of the drawing, where it will be observed that the rails are firmly held upon a series of ties.

The body portion 1 of the tie intermediate its ends is provided with an oblong opening 12 whereby the tie can be filled with concrete, ballast or similar material and tamped, after the same is positioned upon a roadbed.

When the ties are of equal length and the protuberances 5 and 6 properly formed, that is, the proper distance from the ends of the tie, it will be possible to easily gage the width of a track when laying the same.

We do not care to confine ourselves to the size, proportion or minor details of construction, as such changes as are permissible by the appended claims, may be resorted to without departing from the spirit and scope of the invention.

What we claim and desire to secure by Letters Patent, is:—

The combination with rails, of a series of metallic ties having body portions, depending side flanges, angularly disposed ends, lugs or protuberances carried by said ties for gaging the rails, fasteners punched from the body portions of said ties and holding said rails, said ties being arranged whereby said fasteners and said protuberances alternately hold said rails substantially as described.

In testimony whereof we affix our signatures in the presence of two witnesses.

LA VERNE SIMPSON.
JACOB STEIN.
